UNITED STATES PATENT OFFICE.

EDWARD C. JONES, OF KANSAS CITY, MISSOURI.

RAILWAY.

SPECIFICATION forming part of Letters Patent No. 349,846, dated September 28, 1886.

Application filed December 5, 1885. Serial No. 184,789. (No model.)

To all whom it may concern:

Be it known that I, EDWARD C. JONES, a citizen of the United States, residing at Kansas City, in the county of Jackson and State of Missouri, have invented certain new and useful Improvements in Railways; and I do hereby declare that the following is a full, clear, and exact description of the invention, which will enable others skilled in the art to which it appertains to make and use the same, reference being had to the accompanying drawings, forming a part of this specification.

My invention has for its object the construction of a light durable tie for railway-track rails, in which are combined the means for securing the track-rails to the tie and enabling the adjustment of the securing devices independently of said tie, to enable the tie to retain itself upon its own foundation, and for interposing a cushion between the track-rail and its foundation for averting the concussion.

In the drawings, Figure 1 is a perspective view of a railway-track and of my improved tie and adjustments. Fig. 2 is a plan view of the track, and showing the relative position of the single and double plate tie. Fig. 3 is a side view of the track in elevation, showing the bridge-tree between opposite ties. Fig. 4 is a transverse view of one of the tie-plates, showing the means for securing adjustably the rail to the tie. Fig. 5 is a view of a tie detached from the rail, and Fig. 6 is an edge view of the tie-plate. Fig. 7 is a view of the clutch detached from the tie. Fig. 8 is a view of the self-locking ratchet-key. Fig. 9 is a view of the bridge-tree. Fig. 10 is a transverse sectional view taken on the line $x-x$ of Fig. 9.

In the construction of my invention I place in the road-bed, at suitable intervals apart in the direction of and beneath the track of a railway, the piers A A. These piers are preferably made of a size to admit of the reception of a covering flanged plate, as hereinafter described, and are placed in position in series in an independent relation to each other beneath the track-rails C, a concrete base being first prepared and the piers A A mounted thereon. I then form from metal of suitable thickness a longitudinal plate, B, having the usual length and height of an ordinary railroad-tie,

which I mount edgewise upon the piers A A. To the opposite end portions of the tie B, and upon opposite sides, I secure by means of rivets b^3 the flanged plate b^3 , one portion, b , of which plate is made the relative height of the tie-plate B and fits closely thereto. The opposite portion, b' , is bent and extends at right angles from the lower portion of said plate a distance sufficient to cover the portion of piers A upon one side of said pier, and a portion of the flange bent over the pier upon an opposite side to that having said fulcrum equidistant from its center, from which point the portion b' of the flanges are of equal length. A fulcrum, b^3 , is extended from said flanges in the longitudinal direction of the tie outwardly from the ends and over the edge of the pier A. An anchor, D, is attached to the fulcrum b^3 at one end, a portion of which is bent so as to enter the recess a' in the pier a , the opposite end of which anchor extends outwardly from the pier A, and leverage is applied which serves to anchor the tie to the pier. The anchor or lever is carried so far beyond the pier A that when ballast is placed between the tracks the weight of the ballast will serve to bind upon and keep the lever permanently down and under a tension sufficient to hold an anchorage of the tie to the pier.

To prevent the rails from spreading in the top of each tie, at opposite ends, and to keep them at the proper distance for the gage of the track, I make the transverse track seats or recesses b^6 toward the end of the tie. The said recesses are made at an acute angle, as b^7 , on the outer sides to receive the outer edge of the T-rail, the inner side of the recess or seat being made in a vertical relation. The depth of the rail seat or recess is slightly greater than the bottom or flange of the said T-rail.

The opposite ties B B are joined together by means of bridge-tree F, which extends from one to an opposite tie beneath the rails C C.

In the construction of the bridge-tree F, I first make a rectangular box, F', by turning upward at right angles the sides f of a sheet of metal, leaving the top open and extending the said sides a sufficient distance beyond the bottom to make the flanges $f f'$, which I bend outwardly in opposite directions, as seen in Fig. 100

9. I then rivet the flanges $f f'$ of the bridge-tree at opposite ends to the opposite ties B B', the said bridge-tree resting at opposite ends upon the top b' of the tie-flange $b b'$. I then 5 make a rectangular box, F', by bending the sides of a flat piece of metal at right angles and making the box of the proper length and width to fit within the tree F, first inverting the box so that the bottom is presented upwardly to the rail, C, so that when the box F' is 10 in place a support or bearing is afforded for the rail C C proportionate to the span between said ties. The rails C C are carried along from one recess b^6 in one tie to an opposite recess as 15 soon as the ties are in place and dropped within said recesses or seats.

To fasten the rails in the recess or seat b^6 in the ties B, I make a lever or clutch, E, one end of which is made to fit upon the top of the 20 lower flange of the T-rail, and to the contour of said rail, and pivot said lever by a pivot, e, at a point near the top of and to the tie. The opposite end of lever E is carried within a suitable distance of the key-seat B', which extends 25 in a line with the lower edge of the tie, and from one to an opposite tie, and riveted thereto to permit the self-locking ratchet-key H to be wedged beneath the outer end of clutch or lever E. Upon an opposite tie is provided 30 a similar lever, E, in opposite relation, and the ends of opposite levers are joined together by means of a cross-bar, e', extending from one to an opposite bar. I then make a self-locking ratchet key or wedge, H, and with ratchet-teeth 35 h upon the incline of said key or wedge, and the rail C being in place in recess b^6 , I introduce the key or wedge beneath the cross-bar e' near the end of lever E, upon key-seat B', and drive said key or wedge toward the track-rail C, 40 which depresses the opposite end of the said clutch or lever and tightens on rail C, and the portion of the cross-bar e' which enters the ratchet h is held securely from removal, it being necessary to remove the pivot e to remove 45 the key before the T-rail can be moved. Should at any time the rail C become loose in the recess b^6 , a slight blow upon the key H raises the end of lever E against the T-rail, and this adjustment can be made at will without danger 50 of the wedge becoming loosened. The ratchet-teeth upon the incline of the wedge or key H are so constructed that when driven in beneath the clutch E the lower inner edge or heel of the cross-bar e of said clutch rises upon the 55 incline of the wedge, and of the ratchet-teeth which are toward the cross-bar, and drops in the notches between the inclines of the ratchet-teeth and locks as driven in, the inner edge of the cross-bar of said clutch being made at an 60 angle, or extended downward a slight distance, as seen in Fig. 4, so that the said lower edge may fit the notches and inclinations in the same manner that follows the action of a pawl. I may make in the cross-bar of said clutch at 65 the bearing point where the key is driven in and from beneath said cross-bar a recess or notch to prevent lateral movement.

I have shown in Fig. 1 the single-plate tie and the double or twine tie, the only difference in construction being a closer assemblage 70 of parts. When two tie or flanged plates are placed near each other, the tie to which said plates are attached is made the usual height for the track C to rest upon. In this manner the clutch or lever E also rests upon the tie, 75 and between the cross-bar and the top of the tie the key H is driven to wedge the clutch down upon the flange of the rail.

For the purpose of preventing the concussion and deadening sound and lessening the resistance to the blows of the wheel in the movement of a train, I place between the flange b' of the tie B and the top of the pier A a packing, a, made from any yielding material, such as paper, rubber, or other analogous material 80 in one or more layers, so as to constitute a medium for preventing concussion and deadening sound, that the sound shall not be conducted through or by medium of the rail; also, within the bridge-tree F I place a filling, c, as 85 seen in Fig. 10, over which the rectangular box F' is placed, and a packing of rubber or paper placed over the said filling when the box is in place, and upon the portion of the box F', covering said filling, the sides of said 90 bridge-tree F being slightly higher than the top portion of the box F', or of a sufficient height to allow for the thickness of the rubber or paper introduced, and upon which track-rail C rests. 95

I am aware that elastic substances have been placed between the track-rail and the tie for a bearing for said rails; but the vibration incident to heavy concussion is not sufficiently distributed to prevent the shock from a heavily-loaded train, as the compression and concussion occurs at the same moment, and the bearing-point of the rails is usually upon a limited surface. I place my cushion between the opposite ties and upon the bridge-tree 100 and over the filling in the bridge-tree to afford, first, a broad field or surface upon which the rubber or equivalent material may have width and thickness sufficient to counteract the shock, and which, if interposed between the rail and tie, acts to render the fastening to the rail insecure, and permits the rail to sway in opposite directions; second, to permit the vibration to be distributed equally through the track-rails and also through the ties. 115

The portion b' of the flange-plate which lies upon the pier A is punctured or formed so as to retain the packing or cushion interposed between said flange and pier in its proper position.

Having fully described my invention, what I 120 now claim as new, and desire to secure by Letters Patent, is—

1. In railways, the combination, with the bridge-tree, of a suitable filling therein and packing upon said filling, for the purpose 125 specified.

2. The combination, in railways, with a suitable foundation, of a tie and a plate removably attached to said foundation, having an upright

- flange extending from said plate and said foundation and rigidly attached to said tie, whereby the spreading of the track-rails upon the foundation is prevented.
- 5 3. In railways, the combination, with a suitable foundation or support, of a covering-plate, packing interposed between said covering-plate and said foundation, and suitable retaining devices on said covering-plate, for the purpose described.
- 10 4. In railways, the combination, with a suitable foundation or support, of a plate adapted to support a tie removably attached to said foundation, and having one portion of said plate engaging with said foundation, and a lever fulcrumed upon an opposite portion of said plate and engaging with said foundation, as and for the purpose specified.
- 15 5. In railways, the combination, with a suitable foundation or support provided with a suitable recess, of a flanged covering-plate and tie rigidly attached together and arranged upon said foundation, and adapted to engage upon one side with said foundation, and a lever fulcrumed upon said flanged covering-plate and upon an opposite side of said flanged plate, and
- adapted to engage with said recess in said foundation, as described.
6. In railways, the combination, with a suitable tie, of the track-rails and an adjustable clutch or lever, and means for locking said lever or clutch, as described.
7. In railways, the combination, with a suitable tie, of the track-rails and an adjustable clutch or lever, and a self-locking ratchet-key, substantially as specified.
8. In railways, the combination, with a suitable tie having a recess to admit and retain the rail, of a clutch or lever for adjustably retaining said rail in said recess and a self-locking ratchet-key, as described.
9. In railways, the combination, with the bridge-tree, of an inverted box adapted to afford a rest for the track-rails, as described.
- 20 10. In railways, a tie constructed with opposite longitudinal side plates and intermediate filling, as described.
